(57) **CLAIM**

The ornamental design for a wall cabinet, as shown and described.

DESCRIPTION

FIG. 1 is a top, front, and right side perspective view a wall cabinet showing our new design;

FIG. 2 is a front elevational view thereof, the ornamental design not being visible in a rear elevational view, top plan view or bottom view; and,

FIG. 3 is an enlarged fragmentary view of the pattern on the wall cabinet doors thereof.

The broken-line disclosure of the wall cabinet forms no part of the claimed design.

The characteristic feature of the ornamental design resides in the use of the pattern on the wall cabinet doors.
